SPARK PLUG

Edward W. Mitchel, Detroit, Mich.

Application May 23, 1932, Serial No. 612,880

2 Claims. (Cl. 123—169)

This invention relates to spark plugs for internal combustion engine use, and has for its object an improved organization of parts whereby all parts liable to impairment under long use are rendered quickly and cheaply replaceable, and the wastage of certain expensively machined parts incident to the discarding of poorly firing plugs is largely avoided. Another cause which contributes heavily to the inefficiency and early dis-
 5 carding of many of the present forms of spark plug centers about the fact that the anode and cathode terminals between which the spark occurs are mounted upon individually separate and removable parts of the spark plug assembly, quickly and cheaply replaceable, and the wastage of certain expensively machined parts incident to the discarding of poorly firing plugs is largely avoided. Another cause which contributes heavily to the inefficiency and early dis-
 10 carding of many of the present forms of spark plug centers about the fact that the anode and cathode terminals between which the spark occurs are mounted upon individually separate and removable parts of the spark plug assembly, quickly and cheaply replaceable, and the wastage of certain expensively machined parts incident to the discarding of poorly firing plugs is largely avoided. Another cause which contributes heavily to the inefficiency and early dis-
 15 as for example one on the metallic outer shell and the other upon the porcelain center. The comparatively slight variances in the spacing between these terminals, due to variances in the fit of the component parts in different spark plug units as assembled, even though of only a minute fraction of an inch difference, often make for either the successful functioning of the spark plug assembly or its failure as a spark-furnishing medium. As will be hereinafter pointed out, in my construction, on the other hand, the insulator body, preferably of porcelain or some well-known equivalent material, carries both spark-producing terminals whose careful adjustment and spacing can be cared for incident to its manufacture, thus avoiding condemning variances in the distance between the terminals incident to the supported presence of one terminal upon the outer shell. quickly and cheaply replaceable, and the wastage of certain expensively machined parts incident to the discarding of poorly firing plugs is largely avoided. Another cause which contributes heavily to the inefficiency and early dis-
 20 units as assembled, even though of only a minute fraction of an inch difference, often make for either the successful functioning of the spark plug assembly or its failure as a spark-furnishing medium. As will be hereinafter pointed out, in my construction, on the other hand, the insulator body, preferably of porcelain or some well-known equivalent material, carries both spark-producing terminals whose careful adjustment and spacing can be cared for incident to its manufacture, thus avoiding condemning variances in the distance between the terminals incident to the supported presence of one terminal upon the outer shell. quickly and cheaply replaceable, and the wastage of certain expensively machined parts incident to the discarding of poorly firing plugs is largely avoided. Another cause which contributes heavily to the inefficiency and early dis-
 25 units as assembled, even though of only a minute fraction of an inch difference, often make for either the successful functioning of the spark plug assembly or its failure as a spark-furnishing medium. As will be hereinafter pointed out, in my construction, on the other hand, the insulator body, preferably of porcelain or some well-known equivalent material, carries both spark-producing terminals whose careful adjustment and spacing can be cared for incident to its manufacture, thus avoiding condemning variances in the distance between the terminals incident to the supported presence of one terminal upon the outer shell. quickly and cheaply replaceable, and the wastage of certain expensively machined parts incident to the discarding of poorly firing plugs is largely avoided. Another cause which contributes heavily to the inefficiency and early dis-
 30 units as assembled, even though of only a minute fraction of an inch difference, often make for either the successful functioning of the spark plug assembly or its failure as a spark-furnishing medium. As will be hereinafter pointed out, in my construction, on the other hand, the insulator body, preferably of porcelain or some well-known equivalent material, carries both spark-producing terminals whose careful adjustment and spacing can be cared for incident to its manufacture, thus avoiding condemning variances in the distance between the terminals incident to the supported presence of one terminal upon the outer shell. quickly and cheaply replaceable, and the wastage of certain expensively machined parts incident to the discarding of poorly firing plugs is largely avoided. Another cause which contributes heavily to the inefficiency and early dis-
 35 units as assembled, even though of only a minute fraction of an inch difference, often make for either the successful functioning of the spark plug assembly or its failure as a spark-furnishing medium. As will be hereinafter pointed out, in my construction, on the other hand, the insulator body, preferably of porcelain or some well-known equivalent material, carries both spark-producing terminals whose careful adjustment and spacing can be cared for incident to its manufacture, thus avoiding condemning variances in the distance between the terminals incident to the supported presence of one terminal upon the outer shell. quickly and cheaply replaceable, and the wastage of certain expensively machined parts incident to the discarding of poorly firing plugs is largely avoided. Another cause which contributes heavily to the inefficiency and early dis-
 40 as installed as nearly gas-tight as possible. When the porcelain of a spark plug is thus broken, its usefulness is of course gone, and even when, under ordinary service conditions, a spark-plug becomes so fouled that its points can no longer give off the needed ignition spark, it is now thrown away in its entirety, including the still perfectly good nuts, binding posts and other metal parts. This causes an effort on the part of every user to make a spark plug last as long as possible, and
 45 of course a wastage of gasoline and its derivative, the explosive mixture, results in the later stages of its use before being finally discarded. quickly and cheaply replaceable, and the wastage of certain expensively machined parts incident to the discarding of poorly firing plugs is largely avoided. Another cause which contributes heavily to the inefficiency and early dis-
 50 In the improved construction of spark plug here offered a clear structural distinction is made between the really permanent and relatively un-
 55 injurable metal parts, such as the nuts and threaded neck piece, and the spark-producing parts, by forming the latter, including the porcelain insulating body, as a sort of cartridge or removable element which can easily be substituted for a similar one which has outlived its usefulness. Moreover, in forming this part I structurally integrate, with and about the porcelain, a metal shell, which serves to carry one of the spark points on its lower edge and adjacent to the companion point which extends through the center of the porcelain, and which sleeve is as well the recipient, on two of its opposed shoulders or taper, of all of the nut-tightening strain which cannot be breakingly transmitted to the porcelain. Thus a minimum of breakage of porcelain sleeves results, and the very cheapness of the substitutable part, as compared with the present cost of an entire spark plug structure, amounts to an incentive to keep in use and clean only such replaceable fillers as are still new enough to operate with a maximum of efficiency. Such a construction also makes it easy to install various types or sizes of refills in the same metal shell and nut-integrated structure according to the variant ignition requirements of different motors.

My preferred form of construction embodying the improvements hereinabove outlined is illustrated in the accompanying drawing wherein:—

Figure 1 is an elevational view of a completely assembled spark plug.

Figure 2 is a largely sectional elevational view of the spark plug shown in Figure 1.

Figure 3 is a broken away perspective of the same plug designed to bring out even more clearly the inter-relation of the parts.

Figure 4 is a partly broken away and sectional elevational view of a removable filler or partly porcelain cartridge disassociated from the external holding shell.

Figure 5 is a lower end elevational view of the spark plug as illustrated in Figures 1 and 2, being taken along the line 5—5 of the latter and looking in the direction of the arrows there shown.

Figure 6 is a sectional view of the device taken along the horizontal line 6—6 of Figure 2 and looking in the direction of the arrows there shown.

Figure 7 is a partly elevational and partly sectional view of the removable metal collar or sleeve wherein the porcelain insulating body is fixedly positioned incident to the manufacture of this part of the device and before its positioning.

Figure 8 is a partly broken away elevational

view of a fully assembled spark plug of slightly modified form in that provision is made for an annular gas swirling chamber well up toward the middle of the plug as assembled.

- 5 A represents the usual threaded shell, which is designed to be screwed into a correspondingly threaded aperture in the cylinder wall of an internal combustion engine, and B represents the knurled or milled top portion thereof designed 10 to be engaged by the fingers or by pliers when screwing the spark plug in place. As brought out in sectional Figures 2 and 3 particularly, the upper interior face of the shell or collar A is screw-threaded for the engagement therein of the correspondingly threaded annular nut C.

15 It will be noted that the interior bore of the shell A is diminished about half down its length as a whole in order to provide a shoulder D, of substantially the same breadth as the thickness 20 of the wall of the annular nut C and that the diametrical size of the lower portion of the bore is just such as to permit a slip fit therewithin of the metal collar or sleeve E, illustrated by itself in Figure 7. The upper portion of this 25 sleeve is made of larger diameter, beginning at the point F, so as to constitute a shoulder of complementary size and function to that located at the point D in the outer shell, and that the top edge of this enlarged portion of the collar E 30 is preferably, though not necessarily, bevelled, as at E', for the engagement against it after installation within the shell A of the complementarily bevelled lower edge of the annular nut C. The porcelain body H, being held in position within 35 the collar E, particularly by the inbent top edge E' thereof, extends nearly to the level of the bottom edge of said collar E; through its center extends the stem J, the lower end of which projects sufficiently beyond the lower end of the 40 porcelain body H to constitute one of the spark-supplying elements, the inbent terminal G, which is carried by the lower edge of the shell E constituting the other of such terminals. The upper end of this stem being threaded, as at J' for the 45 engagement thereabout of the cap nut K. As brought out particularly in Figures 2, 3, and 4, the lower end of the porcelain body is tapered sufficiently so as to form an air space L between its surface and the interior surface of the sleeve 50 or shell E.

55 In the slightly modified form illustrated in Figure 8 the structural features hereinabove outlined are much the same, except for the fact that, at a position corresponding to the shoulder D in the earlier forms, a double shoulder, as M and N, is formed in the interior of the shell A, thus leaving in addition to the tapering annular space L' a very noticeable annular chamber Q into which the gases swept past the sparking points G' and J' may proceed and be swirled about in a way that has been found to conduct materially to the draught effected cleansing of the spark plug points in the manner already mentioned as to the form shown in Figures 2, 3, and 4. The shoulder 60 M in this form serves as the abutment against which the extreme outer periphery of the shoulder F on the sleeve rests, while the shoulder N marks the line of demarcation between the enlarging space which forms the chamber N and the tapering annular space L' already referred to.

65 As to either form it will therefore be seen that I have provided a spark plug which not only permits very accurate spacing of the sparking terminals, due to the fact that this can be determined as an incident to the manufacture of the removable cartridge as a whole, but as well I have

made it possible to easily and cheaply substitute worn or fouled spark terminals merely by the removal of the relatively inexpensive filler or cartridge constituted by the shell E and the porcelain structure H, without disturbing the relatively expensive machined shell and nut parts which now represent a total loss when substitution of new spark plugs for old ones is indulged in, and which for an indefinite time, indeed as long as the engine structure lasts, can continue to be of unimpaired efficiency.

80 The greatest virtue of this removable filler structure, however, lies in the fact that in its initial installation, as well as at all times thereafter, no strain is put upon the porcelain structure regardless of how tightly the annular threaded nut C may be screwed down within the body A in the effort to make the plug gas tight, since all of the compressive strain is imposed upon the bevelled top edge and the shouldered or tapered portion F of the metal shell; and this strain being truly longitudinal of the filler as a whole falls upon the flared top edge of the metal shell without being transmitted to the easily fractured porcelain body. However, when removal 90 thereof and substitution of a new filler is desired the old one may be lifted out as soon as the annular nut C has been unscrewed.

95 What I claim is:

100 1. In a spark plug construction, an outer supporting bushing having an enlarged and internally threaded upper portion and a smaller downwardly projecting tubular portion, an internal shoulder between said portions of the bushing, a tubular shell having a lower portion freely extending through the smaller tubular portion of the bushing and an enlarged upper portion seated at its lower extremity against said shoulder, an insulating electrode retainer body extending through the shell and projecting from the top 105 thereof and from the supporting bushing and having an enlarged central portion retained within said enlarged upper portion of the shell, said upper portion of the shell being inturned over the top of said enlarged portion of the 110 electrode retainer body, an electrode extending through the retainer body, and a jam nut of lesser internal diameter than the external diameter of the enlarged portion of the shell, encircling the upper portion of the retainer body and bearing 115 against the inturned top portion of the shell.

120 2. In a spark plug construction, an outer supporting bushing having an enlarged and internally threaded upper portion and a smaller downwardly projecting tubular portion, an internal shoulder between said enlarged and tubular portions of the bushing, a generally tubular shell having a lower portion freely extending through the tubular portion of the bushing and an enlarged upper portion seated at its lower extremity 125 against said shoulder, an insulating electrode retainer body extending through the shell and projecting from the top thereof and from the supporting bushing and having an enlarged central portion retained within said enlarged upper portion of the shell, said upper portion of the shell being inturned over the top of the enlarged portion of the retainer body, an electrode extending through the retainer body, and a jam nut encircling 130 the upper portion of the retainer body and bearing against the inturned top portion of the shell, the internal diameter of the jam nut being substantially the same as the internal diameter of the enlarged upper portion of the shell.
